CLAIM

The ornamental design for an office cutter, as shown and described.

DESCRIPTION

FIG. 1 is a top, front, left side perspective view of an office cutter, showing our new design;

FIG. 2 is a top, rear, left side perspective view thereof;

FIG. 3 is a top, rear, right side perspective view thereof;

FIG. 4 is a bottom, front, left side perspective view thereof;

FIG. 5 is a bottom, front, right side perspective view thereof;

FIG. 6 is a front elevation view thereof;

FIG. 7 is a rear elevation view thereof;

FIG. 8 is a left side elevation view thereof;

FIG. 9 is a right side elevation view thereof;

FIG. 10 is a top plan view thereof; and,

FIG. 11 is a bottom plan view thereof.

The evenly spaced broken lines in the drawings and the lightened areas within the broken lines represent a portion of the office cutter that forms no part of the claimed design. The dot-dash broken lines in the figures and the lightened areas within the dot-dash broken lines show environmental subject matter that form no part of the claimed design. The “novium” lettering and icon forming part of the disclosure is a registered trademark of Novium Taiwan Inc.
